UNITED STATES PATENT OFFICE.

EMIL H. GOETZE, OF WALLINGFORD, CONNECTICUT, ASSIGNOR TO INTERNATIONAL SILVER COMPANY, OF JERSEY CITY, NEW JERSEY, AND MERIDEN, CONNECTICUT, A CORPORATION OF NEW JERSEY.

DESIGN FOR A HANDLE FOR CRUMB-SCRAPERS OR SIMILAR ARTICLES.

SPECIFICATION forming part of Design No. 36,425, dated July 14, 1903.

Application filed June 15, 1903. Serial No. 161,636. Term of patent 3½ years.

To all whom it may concern:

Be it known that I, EMIL H. GOETZE, a citizen of the United States, residing at Wallingford, in the county of New Haven, and in the State of Connecticut, have invented a new, original, and ornamental Design for a Handle for Crumb-Scrapers or Similar Articles, of which the following is a brief description, reference being had to the accompanying drawings, forming part thereof, for the special and distinguishing features of the design, and in which—

Figure 1 is a front or plan view of the handle embodying my new design. Fig. 2 is a rear view of the same. Fig. 3 is an edge view. 15

What I claim as new, and desire to secure by Letters Patent, is—

The ornamental design for a handle for crumb-scrapers or similar articles, as shown.

EMIL H. GOETZE.
